UNITED STATES PATENT OFFICE.

JOSEPH H. DOLD, OF PHILADELPHIA, PENNSYLVANIA.

DESIGN FOR A COMBINED BUFFET AND CHINA CLOSET.

Application filed May 24, 1926. Serial No. 17,820. Term of patent 3½ years.

To all whom it may concern:

Be it known that I, JOSEPH H. DOLD, a citizen of Germany, residing at Philadelphia, in the county of Philadelphia and State of Pennsylvania, have invented a new, original, and ornamental Design for Combined Buffets and China Closets, of which the following is a specification, reference being had to the accompanying drawing, forming part therof.

Fig. 1 is a front elevational view of a combined buffet and china closet, showing my new design.

Fig. 2 is a side elevational view of the same.

I claim:

The ornamental design for a combined buffet and china closet, as shown.

In testimony whereof I have affixed my signature this 24th day of April, 1926.

JOSEPH H. DOLD.
